UNITED STATES PATENT OFFICE.

THOMAS KEPPEL NORTH, DECEASED, BY FREDERICK KEPPEL NORTH, ADMINISTRATOR, OF SWAFFHAM, ENGLAND, ASSIGNOR TO VICKERS LIMITED, OF WESTMINSTER, ENGLAND.

RIFLE AND MACHINE-GUN.

1,363,262.

Specification of Letters Patent. Patented Dec. 28, 1920.

Application filed June 13, 1919. Serial No. 304,056.

To all whom it may concern:

Be it known that THOMAS KEPPEL NORTH, deceased, late a subject of the King of Great Britain, whose administrator is FREDERICK KEPPEL NORTH, a subject of the King of Great Britain, residing at "Rougham," Swaffham, in the county of Norfolk, England, did invent new and useful Improvements in or Relating to Rifles and Machine-Guns, of which the following is a specification.

This invention relates to rifles and machine guns (particularly to automatic or self-loading rifles of the gas operated type) of the kind in which the barrel is made readily detachable from the weapon; the chief object of the invention is to make provision for the replacement of one barrel by another in a simpler and more expeditious manner than heretofore.

According to the invention improved means are provided whereby after a locking device has been displaced to its unlocking position, the barrel is free to be detached by a tilting movement *e. g.* by a movement of the muzzle end of the barrel in an upward direction, these means comprising a tooth or projection which is formed on the rear part of the barrel transversely to its axis and fits into a recess in the part to which the barrel is to be attached, in such a manner as to hold the barrel against forward and rearward movements. For this purpose the breech end of the barrel may be formed with a recess to provide at the rear part of the breech end the aforesaid tooth which is preferably of wedge shape and is adapted to fit in a correspondingly shaped recess formed in the wall of the body of the weapon. The said locking device is preferably in the form of a transversely arranged pin which is rotatably mounted in the body of the weapon and is formed with a cut-away portion which, when the pin is suitably adjusted, allows the barrel to be moved as aforesaid.

In order that the said invention may be clearly understood and readily carried into effect the same will be described more fully with reference to the accompanying drawings, in which:

Figures 1, 2 and 3 are sectional side ele-

vations of a weapon constructed in accordance with the invention, Fig. 1 showing the locking device for the barrel in the position in which the barrel is locked to the body of the weapon, Fig. 2 showing the said device in the unlocked position in which the barrel can be detached from the body and Fig. 3 showing the barrel in a position occupied by it during the detaching operation.

Fig. 4 is a transverse section taken approximately through the locking device of Fig. 2 and drawn to an enlarged scale.

Fig. 5 shows the locking means on an enlarged scale, and Fig. 6 shows how the locking pin when in the unlocking position prevents the piston of the gas operated cylinder from reaching the firing position.

A is the body of the weapon and D is the barrel whose rear or breech end is made of generally rectangular shape in cross section as is shown in Fig. 4. b is the recess in the upper surface of the breech end of the barrel and b' is the wedge shaped tooth situated to the rear of this recess and adapted to fit in a correspondingly shaped recess a' (Fig. 3) formed in the upper wall of the body A. It will be observed from Figs. 1 and 2 that when the barrel is in position, the tooth b' fits within the recess a' in the body and the portion of the latter that is situated in front of this recess fits in the recess b in the breech end of the barrel. By displacing the barrel into the position shown by Fig. 3 the tooth b' thereon and the recess b therein come clear of the body and the barrel can then be removed or allowed to fall out. This displacement of the barrel can be effected by simply pressing it on the ground so that it is unnecessary to touch the hot barrel with the hand. The rear under part of the breech end of the barrel is formed with an inclined surface b² to enable the above mentioned displacement of the barrel to occur.

C is the aforesaid locking device which in the example shown takes the form of a transversely arranged pin rotatably mounted in the body of the weapon and adapted to engage with a part-cylindrical recess b³ in the under side of the breech end of the barrel. This pin is cut away as shown in the drawings so that on rotating it from the locking

position shown by Fig. 1 into the unlocking position shown by Figs. 2, 3 and 4 the pin comes completely clear of the barrel, that is to say, the cut away portion of the pin then 5 lies opposite the breech end of the barrel and the barrel can therefore be displaced into the position shown by Fig. 3. The pin C is provided with a handle C' which is held in the locked position shown by chain lines in 10 Fig. 4 or in the unlocked position shown by full lines in the same figure, by a rounded projection c' on the handle engaging in one or the other of two curved depressions in the body of the weapon, the handle providing 15 the necessary resiliency to hold the handle in either of its positions.

Although in the example shown the arrangement is such that the barrel can be detached from the body of the weapon by 20 an upward displacement, the arrangement might be so modified as to enable the barrel to be detached by a sidewise movement or by a downward movement as may be found convenient.

25 In the example shown the weapon is of the gas operated type and the gas operating mechanism comprises a gas vent ring D attached to the barrel and a piston guide tube or gas cylinder D' connected to a hand-guard 30 D². The forward end of this cylinder fits within a recess in the ring D and before the barrel is displaced as aforesaid to remove it the handguard D² is operated to slide the cylinder backward so as to disengage it from 35 the said ring. The aforesaid locking pin C has a recess C^x which is so formed as to permit the backward motion of the cylinder to occur when the pin occupies the unlocked position for enabling the barrel to be angularly 40 displaced for removal. Figs. 2 and 3 show the cylinder D' slid back as stated. When the pin C is in the locked position shown by Fig. 1 a rounded portion thereof bears against the end of the cylinder to lock it in 45 the forward position in engagement with the aforesaid ring. The pin C is also so constructed and disposed that when it is turned into the position shown by Figs. 2, 3 and 4 the rounded surface forms an obstruction to 50 a shoulder e on the piston rod E and so reduces the forward travel of the piston working in this cylinder, thereby not allowing the full action of the mechanism to occur and consequently preventing the gun from being 55 fired unless the barrel is fully locked to the body. When the pin C is turned into the locked position shown by Fig. 1, its cut away portion occupies the position shown in this figure so as to allow room for the piston to 60 pass and complete its forward stroke.

What I claim and desire to secure by Letters Patent of the United States is:—

1. In a rifle or machine gun having a detachable barrel which is removed by a tilting movement, the provision of a co-acting

transverse projection and recess between the barrel and the part to which it is detachably connected, for holding the barrel in position against forward and rearward movements relatively to said part, the barrel tilting about a fulcrum immediately in front of said projection and recess, said fulcrum permitting the barrel to be completely detached from said part by tilting the barrel. 70

2. In a rifle or machine gun, the combination with the body thereof, of a detachable barrel which is removed from the body by a tilting movement, a projection on the rear part of the barrel arranged transversely to 80 the axis thereof, and a recess in the body in which recess the projection fits to hold the barrel against forward and rearward movements, the barrel tilting about a fulcrum constituted by part of the body immediately 85 in front of said recess.

3. In a rifle or machine gun, the combination with the body thereof, of a detachable barrel which is removed from the body by a tilting movement, a wedge-shaped projection arranged on the rear part of the barrel transversely to the axis thereof and a correspondingly shaped recess in the body in which recess said projection fits to hold the barrel against forward and rearward movements, the barrel tilting about a fulcrum constituted by part of the body immediately 95 in front of said recess.

4. In a rifle or machine gun, the combination with the body thereof, of a detachable 100 barrel which is removed from the body by a tilting movement, a recess formed in the rear part of the barrel to provide a projection disposed transversely to the axis of the barrel and a recess in the body in which latter recess said projection fits to hold the barrel against forward and rearward movements, the barrel tilting about a fulcrum constituted by the part of the body fitting in 105 said recess in the barrel. 110

5. In a rifle or machine gun, the combination with the elements claimed in claim 1, of a transversely arranged pin adapted to engage in a recess in the barrel to lock the latter in position and formed with a gap 115 to allow the barrel to be removed when required, and means for rotating the pin to and from its locking position.

6. In a gas operated rifle or machine gun having a detachable barrel which is removed by a tilting movement, the combination with the gas cylinder and the part of the barrel in which this cylinder normally engages, of adjustable means for locking the barrel in position and unlocking it as required, said means when in the locking position preventing the cylinder from being disengaged from said part of the barrel. 120

7. In a gas operated rifle or machine gun having a detachable barrel which is re- 125 130

- moved by a tilting movement, the combination with the gas cylinder and the part of the barrel in which this cylinder normally engages, of a rotary pin arranged transversely to the axis of the barrel for locking the barrel in position and unlocking it as required, said pin when in the locking position preventing the cylinder from being disengaged from said part of the barrel.
10. 8. In a gas operated rifle or machine gun having a detachable barrel which is removed by a tilting movement, the combination with the gas cylinder, of adjustable means for locking the barrel in position and unlocking it as required, said means when in the unlocking position forming an obstruction at the rear part of said cylinder to restrict the forward movement of the piston rod of the gas operated cylinder and thereby prevent the weapon from being fired.
15. 9. In a gas operated rifle or machine gun having a detachable barrel which is removed by a tilting movement, the combination with
- the gas cylinder, of a rotary pin arranged transversely to the axis of the barrel for locking the barrel in position and unlocking it as required, said pin when in the unlocking position forming an obstruction at the rear part of said cylinder to restrict the forward movement of the piston rod of the gas operated cylinder and thereby prevent the weapon from being fired.
10. In a gas operated rifle or machine gun, the combination with the body thereof and a detachable barrel, of a socket in said body in which the rear end of the barrel fits, and means for permitting said barrel to be placed in position and held in said socket against longitudinal movement and to be completely detached therefrom merely by a tilting movement of said barrel.

In testimony whereof, I affix my signature.

FREDERICK KEPPEL NORTH,
Administrator of said Thomas Keppel North, deceased.
